UNITED STATES PATENT OFFICE.

HERMAN WATERMAN, OF NEW YORK, N. Y.

DESIGN FOR A GAS-STOVE BASE.

48,846.

Specification for Design.

Patented Apr. 4, 1916.

Application filed January 24, 1916. Serial No. 74,050. Term of patent 7 years.

To all whom it may concern:

Be it known that I, HERMAN WATERMAN, a citizen of the United States of America, residing at New York city, Manhattan borough, county and State of New York, have invented a new, original, and ornamental Design for a Gas-Stove Base, of which the following is a specification, reference being had to the accompanying drawing, forming part hereof, which represents a perspective view of a gas-stove base, showing my new design.

I claim:

The ornamental design for a gas-stove base as shown.

Signed at New York city, New York, this 21 day of January, nineteen hundred and sixteen.

HERMAN WATERMAN.

Witnesses:

MAURICE BLOCK,
EDWARD A. JARVIS.
